UNITED STATES PATENT OFFICE

99,872

DESIGN FOR A LAMP SHADE

Harry M. Laxer, New York, N. Y., assignor to Idealite, Inc., New York, N. Y., a corporation of New Jersey

Application March 19, 1936, Serial No. 61,695

Term of patent 3½ years

To all whom it may concern:

Be it known that I, Harry M. Laxer, a citizen of the United States and a resident of the city, county, and State of New York, have invented a new, original, and ornamental Design for Lampshades, of which the following is a specification, reference being had to the accompanying drawing, forming part thereof, in which

showing my new design.

Figure 3 is a bottom plan view thereof.

I claim:

The ornamental design for a lampshade as shown.

HARRY M. LAXER.
